UNITED STATES PATENT OFFICE.

LOUIS GODDU, OF WINCHESTER, ASSIGNOR TO JAMES W. BROOKS, TRUSTEE,
OF CAMBRIDGE, MASSACHUSETTS.

MACHINE FOR MAKING SHOE-SOLE WIRE.

SPECIFICATION forming part of Letters Patent No. 360,428, dated April 5, 1887.

Application filed September 1, 1884. Serial No. 141,936. (No model.)

To all whom it may concern:

Be it known that I, LOUIS GODDU, of Win-
chester, county of Middlesex, State of Massa-
chusetts, have invented an Improvement in

5 Mechanism for the Manufacture of Sole-Fast-
ening Wire for Boot and Shoe Work, of which
the following description, in connection with
the accompanying drawings, is a specification,
like letters on the drawings representing like
10 parts.

My invention has for its object the produc-
tion of a machine by which to form in wire
a series of helical channels, leaving parts of
the wire between the said channels elevated to
15 constitute helical projections or screw-threads,
the said channels being concaved at bottom,
and being preferably corrugated or indented
to increase the hold of the fastenings cut from
the wire when inserted into the material to be
20 held together by the said fastenings, the said
wire, by reason of the helical grooves therein,
rotating slightly as it is being inserted into
the leather.

This invention consists, essentially, in a ma-
25 chine for forming helical channels or screw-
threads upon wire, the said machine contain-
ing as elements a series of positively-rotated
axles having disks to act upon and indent the
30 surface of the wire, and means for rotating
the said wire, and also the disks, so that the
surface speed of each shall be substantially
the same, thereby avoiding twisting strains,
as will be described.

My invention also consists in the combina-
35 tion, with reels or spools for delivering and for
taking up the wire and rotating the same, of
a support for the wire and a series of disks
arranged on axles the centers of which are
40 placed at acute angles with relation to the axis
of the wire, the axles converging in the direc-
tion of the movement of the wire toward the
said disks, and, as herein shown, the edge of
each disk forming an independent channel.
45 The surface speed of rotation of the wire and
the surface speed of rotation of the disks are
substantially the same, to thereby avoid twist-
ing strain upon the wire, which would occur
were either the wire or the disk rotated solely
50 by pressure one against the other; or, in other
words, the surface speed of rotation of the

wire is substantially that which it would de-
rive from the disks alone if the wire were not
rotated positively by gearing, as will be de-
scribed.

Prior to my invention a wire or rod has been 55
acted upon at its periphery by means of
equivalent disks secured to shafts, the said
disks acting upon the wire—as, for instance, in
United States Patent No. 181,010; but never
prior to my invention have the wire and disks 60
been rotated positively at the same surface
speed.

Other features of my invention will be here-
inafter specifically described, and pointed out
in the claims at the end of this specification. 65

Figure 1 is a plan view of a machine em-
bodying my improvements; Fig. 2, a side ele-
vation thereof; Fig. 3, a section of Fig. 2 in
the dotted line xx ; Fig. 4, details of the heart
and device operated by it to insure the wind- 70
ing of the wire from end to end of the barrel
of the spool or reel; Fig. 5, a perspective
view and cross-section of a piece of the fast-
ening-wire; Fig. 6, a sectional detail to show
the guides and supports for the wire between 75
the points where it is acted upon by the disks,
and also the head or block which supports the
axles on which the disks turn, and the cap.
Fig. 7 is a view of that part of the machine
immediately at the right of the dotted line $x'x'$ 80
 x' , Fig. 2, the cap e' being, however, removed
to show the disks in place. Fig. 8 is a detail,
in longitudinal section and elevation, of a bearing
for a disk-carrying axle; and Fig. 9 is a
section of the device of Fig. 8 in the line x^2x^2 . 85

The bed-plate A has suitable uprights, A' 90
A² A³, to sustain bearings for the working
parts. The main shaft B has fast upon one
end of it a clutch part or friction-disk, B', and
loose on the said shaft, at one side of the said 95
disk, is a pulley, B², having, preferably, a coni-
cal recess to engage the conical face of the
said disk frictionally and rotate the same and
the shaft B, all as usual, when the loose collar
B⁴, provided with an annular groove, (see Fig. 95
1,) is moved on the said shaft by the hand-
lever B⁵, the inner end of which is adapted, as
usual, to engage and operate the said collar.

In regular operation the hand-lever B⁵ holds
the collar B⁴ pressed against the hub of the 100

loose pulley B², the said hand-lever being held in place by the short arm of a trip-lever, C, pivoted at C', the lever B³, so held, causing the shaft B to be rotated. The longer arm of the trip-lever C is the heaviest, and rests normally upon a pin, C². The elevation of the long arm of the trip-lever C releases the hand-lever B³, and relieves the pressure of the collar B⁴ on the hub of the pulley B² when the hub stops.

10 The shaft B, extended through the bearing A⁵, has attached to or formed as an integral part of it the enlarged head B⁵, which is fitted into the bearing A⁶. At its rear end the enlarged head is provided with gear-teeth 2, which engage a toothed gear, a, and stud a'; and the said gear, by a pinion, a², attached to it, engages a toothed gear, a³, on and drives the shaft b, which, extending along the side of the machine, is provided with the pinion c and the 20 toothed gear d, to be described.

The gear d engages a pinion, d', secured to the toothed gear d², which last-named gear is loose on the stud d³, which said stud is secured to the upright A³; and the said gear d² engages 25 the gear d⁴, fastened to the tubular neck of the rotating yoke or frame d⁵, which supports the shaft or pin d⁶, on which rotates the reel or spool d⁷, which contains the wire to be acted upon, the neck of the said yoke or frame being 30 extended through the bearing d⁸ of the upright A³. The wire led from the said spool d⁷ through the said neck is passed through the guide or support e, firmly secured in the cap e', attached by suitable screws, e², to the head f, the said 35 head being in turn secured to the upper end of or made part of the upright A². The wire from the guide e is led into the conical end of the auxiliary guide or support e³, held in the said head, and thence the wire is led to the 40 take-up reel or spool E, composed of a number of parts to be described.

The enlarged head B⁵ of the main shaft B is bored to receive the shaft g, which has fastened to its rear end the pinion g'. The pinion 45 g' engages the teeth of a stationary gear, g², secured to the bearing A⁵, and as the main shaft and its enlarged head are rotated the pinion g' has a planetary motion about the gear g². The end of the shaft g opposite the 50 pinion g' is extended into the bearing or block o⁴, and is provided with a worm, g³, (best shown in Fig. 3,) which engages worm-teeth cut into the hub g⁵ of a flanged collar, g⁶, thus rotating the said collar, the collar having frictionally 55 attached to it the take-up reel or spool E. This take-up reel or spool is composed, essentially, of a stem, 6, a head or disk, 5, a barrel, 4, and a flange, 3, and with these is a disk, 7, which is secured to the head 5 by a suitable nut, 8, 60 and a ring, 9, which is placed at the rear or inner side of the said flanged hub, and is secured to the said head by suitable screws, 10, the shanks of which screws below their heads are surrounded by spiral springs, as shown in 65 Fig. 3. Between the flanged hub and the collar 9, I introduce a friction-washer, 12, preferably of leather, to thus enable the spool or

reel to slip more or less on its driver, (the flanged hub,) to thus enable the reel or spool to slip with relation to the rotating hubs g⁴ 70 as the mass of wire wound thereon increases in diameter. The head f has bolted to it in this instance three bearings, h h h, that receive the axles h', which are placed in an acute-angle position with relation to the center of the 75 guide e³, and consequently of the wire to be acted upon. Each of these axles has fastened to it a disk, h², having an edge of substantially the thickness of the width of the channel, m', which it is desired to make in the wire m, the 80 said edge being adapted to thus corrugate the bottom of the helical groove m' and enable the wire the better to retain its position in the leather or material, especially when the thread is of long pitch. Each axle has fastened upon it a toothed gear, h⁴, which is engaged and rotated by the teeth of a large bevel-gear, n, bolted to the toothed gear n', the gear n having its bearing upon the neck of the head f, as shown best in Fig. 6. The gear n' is driven from the shaft 90 b by the pinion c and intermediates c' c².

In Fig. 7 it will be noticed that the acting edges of the disks bear the same relation to the center line or axis of the rotating wire that the helical channels m' are to bear with relation 95 to the center line of the wire.

The surface speed of rotation of the wire, derived, as herein shown and as before described, from the rotation of the reels or spools by means of the gearing described, and the surface 100 speed of the disks h², are substantially the same, thereby avoiding twisting strain upon the wire, or, in other words, the surface speed of rotation of the wire is substantially that which it would derive from the disk alone if the wire 105 were not rotated positively by gearing.

To manufacture screw-threaded wire, or to provide wire of comparatively small diameter with screw-threads, I have found it extremely desirable, to avoid straining and twisting the 110 wire and breaking it off, that the disks or devices which indent the wire spirally or helically, as well as the wire itself, shall be rotated positively independent of each other, and by means which shall give to each substantially 115 the same rate of surface speed at the contacting points of the disks and wire.

To wind the wire evenly and in uniform layers on the reel or spool E, I have provided a slotted finger, o, which is connected with and 120 so as to form part of a sliding bar, o', provided with a toe, o², (see Fig. 4,) and guided in the bearing o³, placed at the end of and forming a part of the bearing or block o⁴. The toe of the slide-bar o' is kept against the heart-cam o⁶ by the 125 spiral spring o⁷, and the said heart-cam derives its motion of rotation from a shaft, p, provided with a worm-toothed pinion, p', which is engaged and rotated by the worm p², forming part of the spool-stem 6, before described. The wire between the auxiliary 130 guide e³ and the traverse-bar is passed over one end of a stop-lever, 20, the hub of which is mounted upon the hub-like end 21 (see

Fig. 3) of the bearing or block o^4 , so that the said stop-lever rotates in unison with the shaft B. The short arm of the stop-lever 20 is acted upon by a suitable spring, 22, and the short end of the said lever is held by the pressure of the wire upon its long end at such inclination as to keep the short end of the said lever out of range of the end of the trip-lever C and against the pressure of the spring 22, so long as the wire is unbroken or the spool is not fully filled; but should the wire break or the spool E become fully filled the lever 20 is permitted to turn under the action of the spring 22, and thereafter in the rotation of the shaft B in the direction of the arrow thereon (see Fig. 2) the short end of the said lever 20 strikes the long end of the trip-lever, releases the lever B⁵, and effects the stopping of the machine. By the time that the spool is full the angle formed in the wire between the mass of wire wound on the spool and the end of the auxiliary guide e^3 is sufficient to remove the wire from the lever 20.

The pin 24 limits the movement of the lever 20 in opposition to the spring 22. The wire m (shown dotted in Fig. 6) is held by the guides $e\ e^2$ at each side the point where it is acted upon by the disks h^2 .

The gears h^4 have annular grooves, which are entered by the forked plates h^{10} , adjustably held in place by the bolts h^{12} , the said plates preventing end-thrust of the shafts h' .

In another application, Serial No. 168,007, filed June 8, 1885, I have shown an organized machine for providing wire with threads by the action of rolls which roll against the wire; but in that application the rolls, in addition to their rotation about their own axes, have a revolution about the wire, or, in other words, have a planetary motion.

I claim—

1. The rotating shaft b , the reels or spools d^7 and E, and intermediate gearing to rotate

the same to effect the rotation of the wire, and the head and guides or supports for the wire, combined with the disks and means to rotate the same at substantially the surface speed of the wire, for the purposes set forth.

2. In a machine for forming helical channels or screw-threads upon wire, the combination of the following instrumentalities, viz: a guide or support for the wire, a series of positively-rotated axles having attached disks to act upon and indent the wire, and means to rotate the said wire, whereby the surface speed of the independently-rotated disks and wire at their point of contact are substantially the same, thereby avoiding twisting strain upon the wire, substantially as set forth.

3. In a machine for forming helical grooves or screw-threads in wire, the rotating shaft B, the reel or spool E, arranged to be rotated in unison with it, and means, substantially as described, to rotate the said reel or spool about its own center, combined with the traverse-bar and heart-cam to operate it, and with means to rotate the said heart-cam, substantially as described.

4. The rotating shaft B and its attached reel or spool E, and the stop-lever controlled as to its position by the wire, combined with the trip-lever which is operated by the stop-lever.

5. The rotating shaft 6, the flanged hub mounted upon it, and means to rotate the said hub, combined with the spool E, held frictionally upon the said flanged hub, substantially as described.

In testimony whereof I have signed my name to this specification in the presence of two subscribing witnesses.

LOUIS GODDU.
